UNITED STATES PATENT OFFICE

ROGER W. DISBRO, OF CLEVELAND, OHIO, ASSIGNOR TO THE W. S. TYLER COMPANY,
OF CLEVELAND, OHIO, A CORPORATION OF OHIO

METALLIC WALL STRUCTURE

Application filed May 14, 1927. Serial No. 191,358.

The present invention, relating as indicated to metallic wall structure, more particularly concerns an improved construction for the side walls and ceiling of spray booths. Spray booths are customarily constructed to provide an enclosure open at only one side thereof and to have a suction apparatus operating through the wall furthest from the open side to draw all of the fumes incidental to the spraying operation away from the operator and away from such opening. It is very essential that this suction be employed, both from the health standpoint and for the elimination of fire hazards. Heretofore the walls of these booths have been fabricated from flat metallic sheets having angle irons secured to their adjacent edges and having means for securing together the contiguous faces of the angle irons. Such construction is not only very heavy and expensive, but has been found to ineffectually seal the joint between the wall sections.

My invention provides a much simpler and more satisfactory wall construction which meets the requirement of an air-tight wall joint, and at the same time is lighter in weight and cheaper to manufacture.

To the accomplishment of the foregoing and related ends, said invention, then, consists of the means hereinafter fully described and particularly pointed out in the claims; the annexed drawings and the following description setting forth in detail certain mechanism embodying the invention, such disclosed means constituting, however, but one of various mechanical forms in which the principle of the invention may be used.

In said annexed drawings:—

Fig. 1 is a side elevational view of a spray booth constructed in accordance with my invention;

Fig. 2 a vertical sectional view on an enlarged scale taken on line 2—2 of Fig. 1 through the joint between the side wall and ceiling of the booth;

Fig. 3 a similar view taken on line 3—3 of Fig. 1 through the base line of the side wall; and

Figs. 4 to 9, inclusive, are horizontal sectional views as taken on line x—x of Fig. 1,

illustrating the various modifications in the structural joint between the booth sections.

The illustrated embodiment of the present invention as found in Fig. 1 relates to a rectilinear casing or booth having vertical sides 10, a ceiling or roof 11, a closed end 12 and an open end 13, the flooring therefor being indicated at 14. As mentioned hereinbefore, in the use of this type of spraying booth, there is provided a suction apparatus (not shown), which acts through the wall 12 to prevent circulation of air outwardly of the open side 13. In the following description there will be described in detail the construction of one of the structural units which go to make up the entire booth, it being obvious that a booth of any size may be formed by merely increasing or diminishing the number of such units.

In each of the modifications shown in Figs. 4 to 9, inclusive, is incorporated the main feature of the invention in having the attaching flanges of the units, which comprise the rectangular metallic plates 15, formed to cooperate with each other to provide a rigid and an air-tight joint. Another object hereof is to construct these attaching flanges so that two or more complementary surfaces of each plate 15 are provided for abutment in the assembly of units. This not only strengthens the joint when the plates 15, permitting the use of lighter material, but also provides a more effective air excluding structure.

In Fig. 4 the plates or sections 15 are assembled with their respective extremities 16 in juxtaposition. At the extremities 16 the plates 15 are angularly bent to provide a right-angle flange 17 and also rebent flanges 18 and 19, the portions 18 being parallel to the plates 15 and the portions 19 being parallel to flanges 17. In the assembly of these units each of the several flanges 17, 18 and 19 of the adjacent plates are positioned in close contact and a bolt 20, or like securing means, is employed to secure the sections together. On account of the close contact between the ends of the sections 15 in the several planes incidental to the formation of flanges 17, 18 and 19 the joint formed there-

by is practically air-tight. This construction is found to also provide a very rigid joint.

The form illustrated in Fig. 5 is very similar to that of Fig. 4 having plates 15 provided with angular flanges 17 and 18 at their extremities, which are adapted to contact with each other. In place of the flanges 19 is provided flanges 20 which do not contact at their adjacent faces, but provide a longitudinal pocket or recess 21 therebetween, in which is inserted suitable packing material 22 to aid in the exclusion of light and air from the section joint. In this form the plates 17 are indicated as being secured together by spot welding, which of course renders the structure permanent.

A like construction is illustrated in Fig. 6 wherein the flanges 20 provide the recess 21, but in place of the packing 22 there is inserted in this recess a suitable wedge 23. This latter member may be formed of comparatively light spring metal in the shape of a V, which may be driven into the recess 21 to seal the same. Similarly, Fig. 9 shows a joint between the plates 15 having suitably spaced parallel flanges 20 and another form of sealing device. This device consists of a U-shaped metallic member 24 which is attached to the flanges 20 with its open ends engaging the outer surfaces of such flanges. This U-shaped member is constructed of spring material and serves to not only seal the outer ends of the plates 15, but also to keep the flanges 17 pressed into close contact with each other.

Fig. 8 illustrates a joint having the ends of plates 15 bent into flanges 17, 18, 19 and 20, together with a detachable metallic strip 25 which, when assembled to the joint between plates 15, is adapted to engage the outer surfaces of each of said several flanges. A bolt 26 is provided to secure the ends 27 of member 25 to the flanges 17.

Fig. 7 illustrates a joint having the plates 15 bent at their extremities into right-angle flanges 28 similar to flanges 17 and with oppositely bent portions 29 and 30. Secured to the flanges 29 and 30 is a supplemental plate 31 adapted to have close contact with the outer surfaces of such flanges to prevent air from passing therebetween. This member 31 in this form of joint serves also as a means for attaching the sections 15 together.

The several sections in the construction of a spray booth may be secured to the floor 14 by a right-angle plate 32 having one surface thereof secured by bolts 33 to the floor and having the other surface 34 extending vertically, to which may be attached the lower vertical end of the plates 15. At the upper end of such plates or sections is provided an angular strip having a vertical flange 35 extending closely parallel to the inner surface 65 of the plates 15 and having a horizontal or

laterally projecting flange 36 suitable for the attachment of the ceiling members 37. These members 37 are of similar construction to the sections 15 and may be secured together at their joints in any of the manners indicated in Figs. 4 to 9, inclusive. As shown in Fig. 2, the strip attached between sections 15 and 37 is extended beyond the flange 36 to provide a second vertical flange 38, which serves to strengthen the entire structure, as well as to hide from view the joints in the sealing structure.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. A self-supported metallic wall comprising a plurality of aligned flat sections having integral multi-bent angular flanges at their adjacent edges of Z shape, the surfaces of which are at right angles, two surfaces of the Z shaped flanges on each of said adjacent edges being parallel and in contact, and resilient means engaging the outer portions of said flanges adapted to maintain the abutment of said flanges and render the joint substantially air tight.

2. A self supported metallic wall comprising a plurality of sections having their side edges formed with a right angular flange, the flanges of adjacent sections being parallel and in abutment, other flanges formed at an angle to said first flanges, said last named flanges being also parallel and in engagement with each other, and additional flanges, all of said flanges forming a Z in which the surfaces are at right angles, and means mounted on said flanges for locking said sections together.

Signed by me, this 13th day of May, 1927. 110
ROGER W. DISBRO.
